UNITED STATES PATENT OFFICE.

THOMAS A. MACAULAY, OF NEW YORK, N. Y.

SEWING-MACHINE.

SPECIFICATION forming part of Letters Patent No. 269,218, dated December 19, 1882.

Application filed November 3, 1882. (No model.)

To all whom it may concern:

Be it known that I, THOMAS A. MACAULAY, of the city, county, and State of New York, have invented certain new and useful Improvements in Sewing-Machines, of which the following, with the accompanying drawings, is a specification.

Similar letters refer to like parts.

My invention relates to that class of sewing-machines in which a rock-shaft having an increased axial motion and a rotary feed-operating shaft are used, as hereinafter more fully described.

In the drawings, in which Figures 1 and 2 represent a portion of a sewing-machine, XX indicate the rear part of the bed and arm of a sewing-machine. A is the main shaft. B is the eccentric thereon. C is a pitman connected by pin *a* to bell-crank lever D, the longest arm of which has a slot, *e*. Said lever is pivoted to the bed X by stud F. E is a rock-shaft, which is intended to carry a shuttle by a suitable fixture at its front end, and has a crank, *g*, fixed to its rear end. G is a crank-pin, entering slot *e* of the bell-crank lever D. H is a revolving feed-operating shaft, having a crank, O. I is a pitman-lever connected at one end to the pitman C by stud K, its other end being connected to the crank O by link N and pins L and M. Said lever is fulcrumed at *d* to the radius-bar R, which is pivoted to the hollow arm X by pin *b*.

Motion being given to the main shaft A, the eccentric B imparts a reciprocating motion to the pitman C and the bell-crank D through the pin *a*, and from said bell-crank to the rock-shaft E through the pin G and crank *g*. The pitman-lever I, being fulcrumed at *d* to the radius-bar R and pivoted to the pitman C, receives a vertical and lateral motion. Its lower end passes around the center of the shaft H, and, being connected to the crank O by the link N, gives the shaft H a rotary motion. This rotary shaft is intended to operate a feed-bar by the usual connections.

The pitman-lever may be connected directly to the eccentric by having a wider face on the eccentric, and the pitman-lever having an enlarged eye or strap to span the eccentric; or a separate eccentric may be provided for it, instead of being pivoted to the pitman C at K, and a slot and pin may be used instead of the radius-bar, and other changes may be made without departing from the spirit of my invention.

Having described my invention, I claim—
The combination of the shaft A, eccentric B, pitman C, lever D, crank *g*, and shaft E with the pitman-lever I, radius-bar R, link N, crank O, and shaft H, substantially as set forth.

THOS. A. MACAULAY.
